Patented Dec. 16, 1919.

Inventor
W.W. Stauffer

~~B. Murphy, Jr.~~

UNITED STATES PATENT OFFICE.

WALLACE W. STAUFFER, OF AKRON, INDIANA.

PUZZLE.

1,325,122.

Specification of Letters Patent. Patented Dec. 16, 1919.

Application filed December 27, 1918. Serial No. 268,526.

To all whom it may concern:

Be it known that I, WALLACE W. STAUFFER, a citizen of the United States, residing at Akron, in the county of Fulton and State of Indiana, have invented certain new and useful Improvements in Puzzles; and I do hereby declare the following to be a full, clear, and exact description of the invention, such as will enable others skilled in the art to which it appertains to make and use the same.

My invention relates to improvements in games and more particularly to a war game.

An important object of this invention is to provide a game of the character described adapted for use as a source of amusement for both young and old.

A further object of the invention is to provide a war game wherein the playing board is divided off into a plurality of divisions representing opposing sides and having mobile characters disposed in the divisions and adapted for maneuvering.

A further object of the invention is to provide a game having a board representing the domain of Germany and the Allies, and mobile characters arranged on the board and representing the opposing sides, the object of the game being to capture the character representing Germany.

A further object of the invention is to provide a game of the character described, which is neat in appearance, of highly simplified construction and cheap to manufacture.

Other objects and advantages of the invention will be apparent during the course of the following description.

In the accompanying drawings forming a part of this specification and in which like numerals are employed to designate like parts throughout the same,

Figure 1 is a plan view of a game embodying my invention, showing the characters arranged for starting the game,

Fig. 2 is a plan view of the game showing the characters as they are at the finish of the game, and

Fig. 3 is a central vertical transverse section through the game.

In the drawings wherein for the purpose of illustration is shown the preferred embodiment of my invention, the numeral 5 generically designates the game, which comprises in part a circular base 6 having a

circular rim 7 secured to its periphery. As clearly shown in Fig. 3, the circular rim 7 extends upwardly from the base 6.

The base 6 is divided off into four compartments, three of which are alike and represent the three principal Allies. The fourth division or compartment is of a different size than the remaining divisions and represents Germany, or the domain of the Kaiser. The divisions of the Allies are numbered 8, 9, and 10 and are divided off by radial partitions 11. The radial partitions 11 terminate short of the center of the base 6 and connect with auxiliary partitions 12 forming entrances 13 to the territory of the Allies. The auxiliary partitions 12 are arranged about a central post 14. Within each of the divisions 8, 9, and 10 are a plurality of baffle walls 15 adapted to represent communicating trenches. The baffle walls 15 are so disposed within the several divisions as to require the maneuvering within the divisions somewhat skilful.

The territory of the Kaiser is represented by the numeral 16. The entrance to the compartment 16 is partly obstructed by an L-shaped partition 17. A pair of outwardly diverging walls 18 are disposed within the partition 17 and connect with a plurality of parallel walls 19 representing fortifications.

A ball 20 preferably of a dark color represents the Kaiser and as illustrated in Fig. 1 is disposed in front of the entrance to the Kaiser's domain and on one side of the post 14. The Allies are represented by white balls 22, two of which are deposited in each of the divisions of the Allies at the beginning of the game. An unattached Ally 23 is positioned on the opposite side of the post from the Kaiser. As illustrated in Fig. 2, the object of the game is to imprison the Kaiser between the forts 19 and lodge one of the Allies in each of the forts. The unattached Ally 23 is at the end of the game to be positioned at the entrance of Germany in the position formerly occupied by the Kaiser.

While I have shown and described the preferred embodiment of my invention, it is understood that I may make such minor changes in arrangement and construction of parts, as will remain within the spirit of the invention and scope of the appended claims.

Having thus described my invention, what I claim is:—

1. A game of the character described comprising, a circular base; a plurality of 5 radially disposed partitions arranged on the base and forming compartments adapted to represent the Allies and the Kaiser; baffle walls arranged within the compartments of the Allies; a plurality of walls arranged within the compartment of the Kaiser and adapted to represent fortifications; a baffle wall arranged at the entrance to the compartment of the Kaiser; and mobile characters adapted for maneuvering about the several baffle walls and fortifications.
2. A game of the character described comprising, a circular base; a rim secured about the periphery of the base and extending thereabove; a plurality of radially dis- 10 15 20

posed partitions forming a plurality of compartments, said partitions terminating short of the center of said base, auxiliary partitions connected to the inner ends of said first named partitions and restricting 25 the entrance to said compartments; a plurality of baffle walls arranged in certain of the partitions; a plurality of walls arranged in one of the partitions and adapted to represent fortifications; an obstruction arranged at the entrance of the compartment having the fortifications; and a plurality of mobile characters adapted for maneuvering about the several compartments.

In testimony whereof I affix my signature 35 in presence of two witnesses.

WALLACE W. STAUFFER.

Witnesses:

C. H. STAUFFER,
L. WHITTENBERGER.
